M. D. Moore

United States Patent Office.

MARQUIS D. MOORE, OF BROOKLYN, NEW YORK.

Letters Patent No. 78,116, dated May 19, 1868.

IMPROVEMENT IN BUTTONS:

The Schedule referred to in these Letters Patent and making part of the same.

TO ALL WHOM IT MAY CONCERN:

Be it known that I, MARQUIS D. MOORE, of Brooklyn, in the county of Kings, and State of New York, have invented certain new and useful Improvements in Fasteners for Wearing-Apparel; and I do hereby declare that the following is a full, clear, and exact description of the same, reference being had to the accompanying drawings, making a portion of this specification, in which—

Figure 1 is a plan view of a fastener made according to my invention.

Figure 2 is a transverse section of the same, taken in the line $z z$ of fig. 1.

Figure 3 is a transverse section of the same, taken in the line $y y$ of fig. 1.

Figure 4 is an edge view, showing a modification of the invention.

Figure 5 is a plan view of the same.

Figure 6 is a longitudinal section of the same, taken in the line $z z$ of fig. 5.

Figure 7 is a detached view of one portion of the same.

Similar letters of reference indicate corresponding parts in all the figures.

The object of this invention is to provide a substitute for the common button, which will not only more securely fasten the apparel to which it may be applied, but with which the button-hole required with the aforesaid ordinary button may be dispensed with.

The invention consists in a fastening composed of two interlocking parts or pieces, so shaped and constructed that they may be very readily connected or detached from each other, the desired result being thereby obtained.

The invention further consists in a novel means whereby the most efficient operation of the main feature of the invention is secured.

To enable others to understand the nature and construction of my invention, I will proceed to describe it with reference to the drawings.

The larger portion or piece of the fastening is shown at A, and consists of a disk, preferably of nearly circular form, attached to the desired portion, indicated in red outline at A*, of the garment or article of apparel; by stitches passing through holes formed at or near opposite edges thereof, as shown at a in figs. 1 and 4.

Provided in one side or lateral part of the disk or piece A is a deep recess, indicated at b, which is preferably of tapering form, smallest at its inner end, and which is also of dove-tail shape in its cross-section, being narrowest at the outer surface, a', of the said portion; as shown more fully in figs. 2 and 4. It is much preferred that in addition to its tapering and dove-tailed shape just hereinbefore described, the recess, b, have formed in its sides, and at its inner and smaller end, two notches, b', shown in fig. 1, and the purpose of which will hereinafter appear. It should be mentioned that the recess b of the disk or piece A should extend inward beyond a line drawn from one to the other of the points a, at which the said piece is attached to the article of apparel, in order to secure the more perfect retention in place of the two parts of the device, when the same is in use in fastening such apparel, as presently hereinafter set forth.

The other piece or part of the device is marked B in the drawings, and is made of such shape as to correspond with that of the recess b of the piece A, into which it is designed to fit. This piece B is attached to the desired portion, marked B*, of the garment or apparel by stitches passing through suitable holes provided therein at e. In order to fasten the two parts of the garment or apparel together, the piece B is fitted into the recess b of the piece A, the two pieces, A B, being thus, as it were, interlocked, and the strain upon the said parts of the apparel approximating to that indicated by the arrows in figs. 1, 5, and 6. The piece A is drawn snugly inward against the sides of the aforesaid recess b, and being prevented by its dove-tail form from slipping out toward the outer surface of the disk or part A, is retained in the said recess, and the two parts of the apparel are thus fastened together. Inasmuch as the recess b extends inward beyond the stitches a, which secure the disk or piece A to the garment, the cloth of such garment is drawn tightly across at the side of the inner end of the aforesaid recess, as shown at b*, in figs. 3 and 6, the said tightened portion of the cloth serv-

ing to support the innermost end against any strain tending to tilt the said piece, and which might otherwise bring the same from its place in the recess *b*. Furthermore, when the recess is formed with the notches *b'*, hereinbefore described, the spurs *a**, provided upon the inner end of the piece *B*, to fit into the said notches, assist materially in insuring the secure retention of the piece *B* in its place. When it is desired to detach the two pieces from each other, in order to unfasten the garment, it is of course only necessary to withdraw the piece *B* from the recess *b* in the piece *A*.

Instead of being made of the particular form hereinbefore described, the recess *b*, together with the piece *B*, fitting into the same, may be of any shape desired which will insure the retention of such piece *B* within the recess as set forth; and, furthermore, the lateral studs, and the notches *b'* receiving the same, instead of being provided at the innermost ends of the piece *B* and recess, respectively, may be arranged at the central portions of the same.

What I claim as my invention, and desire to secure by Letters Patent, is—

1. The fastener formed in two sections, *A* *B*, fitted to each other, substantially as shown and described, for the purpose set forth.
2. The lateral spurs *a** of the piece *B*, arranged to act in connection with the notches *b'* at the sides of the recess in the piece *A*, substantially as and for the purpose specified.

M. D. MOORE.
